BOMB SLIP, TOWING GEAR, AND ANALOGOUS RELEASEABLE ATTACHMENT

Reginald Kirshaw Pierson and Reginald Arthur Firman, Weybridge, England, assignors to Vickers-Armstrongs Limited, London, England

Application July 30, 1947, Serial No. 764,800
In Great Britain October 20, 1942Section 1, Public Law 690, August 8, 1946
Patent expires October 20, 1962

7 Claims. (Cl. 74—96)

1

The invention has reference to releasable attachments for use in conjunction with objects such as bombs, mailbags, supply containers or other articles to be dropped from aircraft, or for use in towing operations, and in other analogous circumstances, such attachments being of the type wherein the load-engaging members (e. g. hooks) are released through the medium of a toggle mechanism by an electro-magnetically operated tripping device which, when actuated, imparts a lateral blow to the toggle sufficient to collapse the latter and initiate or effect the releasing operation. The object of this invention is to provide an improved construction of tripping mechanism for a releasable attachment of the type referred to.

In a releasable attachment of said type, the tripping mechanism provided by the present invention comprises a rotary armature carrying a projecting abutment which, when the armature rotates on being energised, impinges upon and imparts a lateral blow to the braced portion of the toggle mechanism, and means for arresting the rotation of the armature when the toggle mechanism has moved to the collapsed position. The tripping device may be applied to a releasable attachment wherein a pair of load-engaging jaws are held engaged by the presence of a movable stop between opposed bearing faces or cooperating parts of said jaws, and in which the arrangement is such that the load itself normally reacts to impose forces tending to disengage the jaws and to eject said stop; in such case the toggle mechanism is arranged normally to impose a restraining force on said stop in a direction opposed to said ejective force and, when released, to withdraw or allow the ejection of the stop on collapsing.

One embodiment of the invention is hereinafter described by way of example with reference to the accompanying drawings, which illustrate the application of a tripping mechanism as characterised by this invention to an attachment suitable for use with bombs and other articles to be dropped from aircraft in flight. In said drawings Figs. 1, 2, 3 and 4 are elevations of the attachment (Fig. 2 being a fragmentary view) as seen when one-half of the enclosing casing is removed, and they illustrate respectively the relative positions of the component parts (a) when supporting a load, (b) immediately after the tripping mechanism has been operated, (c) when the load is completely freed, and (d) when the jaws have automatically resumed their operative positions ready for the mechanism to be re-set. Fig.

2

5 is an end view of the attachment as shown in Fig. 1, with both halves of the casing assembled, and Fig. 6 is a fragmentary detail illustrating a cross-section, taken on the line VI—VI of Fig. 2, of the rotary armature hereinafter described.

It will be seen from the drawings that the attachment comprises a slip, constructed of two complementary recessed parts 59, 60, which when assembled enclose cavities in which the moving parts are contained, said slip being apertured at 61 for connection to a hoisting device of known kind and having two load-engaging jaws 62, 63 mounted upon a common pivot 64. The jaws 62, 63 have pincer-like extensions with opposed plane bearing faces 621, 631 arranged so that the presence of a stop 66 of roller form between such faces retains said jaws in the closed position; said faces 621, 631 are inclined to each other when in the position shown in Fig. 1 and the angle included between them is adjusted in accordance with the friction angles of the material so as to produce a resultant force which tends to eject the stop 66 from between said faces, the operative force being derived from the load which is suspended from a shackle 65 resting upon the tips of the jaws 62, 63 and which tends to force the jaw-tips apart.

The locking mechanism for holding the roller 66 between the jaw-faces 621, 631 incorporates the toggles 67, 68 and 70, 71. The link 67 of the primary toggle carries said roller 66, whilst the link 68 is pivotally anchored at 69. To the central pivot of the toggle 67, 68 is connected the link 70 of the second toggle, which link 70 is pivoted at 71 its opposite extremity to the free end of a bifurcated lever 71 pivoted upon the spindle 72 of a rotary armature 73, which constitutes the electro-magnetically operated striker provided by the invention.

Said armature 73 is almost completely enclosed in a cylindrical cavity 74 formed by the halves 59, 60 of the slip, in the walls of which cavity are inset soft iron cores 75 extending substantially through the two halves 59, 60. The armature comprises windings, indicated conventionally at 76 in Fig. 6, and pole-pieces 80, 81, 82, and 83. Said windings 76 are connected to contacts in the circumferential face of an insulated block 77 which, as the armature 73 rotates between the positions shown in Figs. 1 and 2, cooperate with spring-pressed contact members 78 which are in turn connected to the fixed contacts 79 (Fig. 5). These contacts 79 make connection with corresponding spring-pressed contacts in the inner wall of a housing (not shown) into which the

slip 59, 60 is arranged to be inserted when hoisted into position upon the aircraft. The windings 76 of the armature 73 are mounted upon a spider-like member of which the spokes are constituted by the pole-pieces 80, 81, 82 and 83. The pole-pieces carry outwardly projecting lugs 801, 811, 821 and 831 respectively. The lugs 801 and 831 lie on opposite sides of the bifurcated lever 71.

When the mechanism occupies the position depicted in Fig. 1, with a load supported by the jaws 62, 63, the toggle-members 67, 68 are almost in alignment, so that a great proportion of the force tending to eject the roller 66 from between the surfaces 621, 631, is resisted by the anchorage 69. The remainder of such ejective force tends to displace the link 70 longitudinally towards the left, as viewed in Fig. 1, and this in turn is resisted by the bearing 72 of the armature 73 since the said link 70 and the pivoted lever 71 are braced substantially in alignment.

To break the toggle for the purpose of releasing the jaws 62, 63, the armature current is switched on. The pole-pieces are attracted towards the soft iron cores 75 in an anti-clockwise direction and the consequent rotation of the armature 73 causes the lugs 801 of the pole-pieces 80, lying immediately beneath the lever 71, to impinge against the portions 711 of said lever 71 with an impetus amply sufficient to collapse both toggles and permit the ejective force due to the load on the jaws 62, 63, to expel the roller 66, permitting said jaws 62, 63 to open and so release the bomb shackle 65, as shown in Fig. 3. In order that the armature 73 when actuated may acquire added impetus it is convenient to allow a certain degree of clearance, indicated at 86, between the edges of the lever 71 and the lugs 801, 831 of the adjacent pole-pieces 80 and 83. Helical springs 88 (Fig. 6) having their respective extremities attached to the armature 73 and the non-rotatable spindle 72 are provided for the purpose of constantly urging the armature 73 clockwise (as viewed in Fig. 1). This has the effect, when the armature is not energised, of causing the lugs 831 of the pole-piece 83 to contact the portions 721 of the lever 71 and thereby to hold the latter against an abutment 751, the position of which is carefully adjusted to produce substantial alignment of the toggle 70, 71.

On operation of the armature to disengage the jaws, the magnetic attraction between the pole-pieces and the soft iron cores has the effect of imparting a braking action on the further rotation of the armature as soon as it has passed the position in which the pole-pieces are nearest to the soft iron cores. The impetus of the ejected stop-roller 66 and the toggle-parts associated therewith however is sufficient to carry the armature 73 round to the position shown in Fig. 2, forcing the insulated contact-block 77 past the bulges of the spring contacts 78, so that the armature is stopped and is held in this position with its operating circuits interrupted. In operation, after the shackle 65 has passed the tips of the jaws 62, 63, the latter are returned to their initial positions by springs 87, 87, and the parts then assume the position illustrated in Fig. 4. To re-set the toggles, the armature is given an impetus in the clockwise direction, sufficient to force the block 77 past the bulges of the contacts 78, by a sharp push upon the head 851 of the slidable spring-pressed plunger 85. The inclined face of the tip of said plunger coacts with the side of the pole-piece 83 so that when depressed the plunger pushes said pole-piece 83

sideways and rotates the armature 73, which is by this means and with the assistance of the springs 88 returned to its initial position. The jaws 62, 63 being closed and the space between the surfaces 621, 631 being fully open, the roller 66 is caused by gravity and by said springs 88 acting through the armature 73 upon the toggle 70, 71 to resume its position between such surfaces, carrying the toggle linkage 67, 68 and 70, 71 with it until they likewise have taken up again the position depicted in Fig. 1. The springs 88 also serve to prevent the toggle 70, 71 from bouncing out of the aligned position under jolting or vibration of the aircraft.

If for any reason it is desired to release the toggle mechanism mechanically, this can be effected by a downward push upon the head 851 of the plunger 85. The operative part of the plunger being of wedge-formation, its movement presses a pivoted stop-member 84 laterally from the position shown in Fig. 1 and this motion is communicated to the pole-piece 82 of the armature 73, rotating the armature and breaking the toggle 70, 71 as hereinbefore explained. The thickness of the tip of the member 84 must be such that the rest positions of the armature 73 and of the toggle parts 70, 71 are solely determined by the contact of the lever 71 against the abutment 751.

What we claim as our invention and desire to secure by Letters Patent is:

1. A tripping mechanism for a releasable attachment of the type referred to, comprising a toggle mechanism, a rotary armature carrying a projecting abutment which, when the armature rotates, impinges upon and imparts a lateral blow to the toggle mechanism, electro-magnetic means for rotating the armature, and means for arresting the rotation of the armature when the toggle mechanism has moved to the collapsed position.

2. In tripping mechanism as claimed in claim 1, the arrangement wherein two projections carried by the armature are located one at either side of a movable link in the toggle mechanism so that when the armature revolves in one direction one of said projections impinges on said link to impel it towards the collapsed position of the toggle mechanism, whilst on a reverse movement of the armature the second projection returns said link to the braced position of the toggle.

3. The mechanism claimed in claim 2, wherein a certain degree of lost motion is permitted between the armature projections and the movable toggle-link.

4. A tripping mechanism as claimed in claim 1, wherein the armature is subjected to a magnetic braking action after it has effected the collapse of the toggle.

5. The mechanism claimed in claim 1, wherein the electrical connections to the armature are effected through the medium of stationary contact members in the wall of a chamber housing the armature and cooperating contacts carried in the circumferential face of a portion of the armature, said stationary contacts being spring-pressed and operating to hold the armature in the position occupied when the toggles have been collapsed until it is returned to its initial position by re-setting means.

6. In tripping mechanism as claimed in claim 1, means for re-setting the armature to the locked position of the toggle-mechanism comprising a spring-pressed plunger of which the extremity is arranged when said plunger is manu-

ally depressed to impinge upon an abutment carried by the armature and thereby to rotate the same towards its initial position.

7. In tripping mechanism as claimed in claim 1, supplementary manual means for operating the armature to collapse the toggles.
